UNITED STATES PATENT OFFICE.

PHELPS BROWN, OF SPRINGFIELD, MASSACHUSETTS:

MAGNETO.

Application filed February 25, 1924. Serial No. 695,096.

To all whom it may concern:

Be it known that I, PHELPS BROWN, a citizen of the United States, residing at Springfield, in the county of Hampden and State of Massachusetts, have invented new and useful Improvements in Magnetos, of which the following is a specification.

This invention relates to improvements in magnetos and, more particularly, to magnetos of the so-called reciprocating armature type.

In magnetos of this general type, it has heretofore been customary to move the armature into contact with its poles and to provide mechanism for driving the armature away from its poles at speeds entirely independent of engine speed. Physical contact between the armature and its poles, while desirable from the point of view of low reluctance of the magnetic circuit, necessarily tends to create noise and, while enough has been done in the past to prevent excessive noise of contact in magnetos intended for relatively low speed operation, the prior developments are not sufficient to overcome the noise of contact when the armature is operated at relatively high speeds, such as are necessary when the magnetos are to be used in connection with multi-cylinder engines, such as are used in tractors, trucks, automobiles, aeroplanes and the like. The driving of the armature away from its poles at speeds independent of engine speeds is important in magnetos operated by relatively slow speed engines and it is important in any event for starting purposes. In magnetos operated by high speed engines, however, the armature can be operated at speeds dependent on engine speed and armature speeds equal to, or greater, than the speeds obtained by spring drive of the armature can be obtained.

The present invention is directed to the provision of a magneto intended for operation with relatively high speed engines and the invention seeks to provide a magneto which is suitable for multi-cylinder engines, such as the engines used on tractors, motor trucks, automobiles, aeroplanes and so forth.

In adapting a magneto, of the general class described, for the new and extended field of service above set forth, one of the characteristic features of the magneto, hitherto accepted almost as a landmark, has had to be dispensed with, at least at certain

stages of the magneto operation. This feature is that of physical contact of the armature with its poles. The prevention of such contact at high armature speeds is obviously desirable on account of the ensuing noise. It is also desirable and practically essential to reduce vibration and to prevent excessive wear on the parts which would otherwise occur due to the high speed operation of the armature. At the same time, contact of the armature with its poles may, under certain conditions, particularly at cranking speeds, be desirable.

It is therefore an object of this invention to provide, in a magneto of the general class described, means whereby the armature may be prevented from contacting with its poles, as and when desired.

It is also an object of the invention to provide means whereby the minimum air gap between the armature and its poles may be varied, as and when desired, and preferably, although not necessarily, varied from a predetermined maximum gap to zero.

Another object is to provide means controlled by variation of the minimum air gap for varying the timing of the spark generated.

Another object of the invention is to provide, in a magneto of the general class described, means whereby the electrical output may be varied and controlled, as desired.

Another object of the invention is to provide a specifically improved armature actuating mechanism, characterized in that the armature is operated at speeds proportionate to engine speeds and without the use of elastic driving means, such as springs.

Another object of the invention is to provide an armature actuating mechanism, consisting of a quick throw cam driven by the engine, and connections therefrom to the armature for moving the latter by an inelastic transmission of force,—such connections including a lever, the fulcrum of which is adjustable to control the degree of approach of the armature toward its poles.

Another object of the invention is to provide improved means for controlling the breaker points which open and close the choke winding of the magneto.

More particularly, it is an object of the invention to provide means independent of the armature for controlling the breaker points to the extent of holding them open

for the purpose of enabling the flux to build up rapidly in the magnetic circuit. Ordinarily, the breaker points are connected for operation from the armature and close when the armature closely approaches the poles, thereby forcing the flux to build up against a short circuited choke winding which retards the action. While the latter arrangement is desirable if sufficient time intervals are available, as in magnetos operating at relatively low armature speeds, it is not commercially satisfactory in the present case where high speed operation of the armature is desired and where a rapid building up of flux is consequently necessary.

Other objects and advantages will appear in the following description and in the illustrative embodiment of the invention in the accompanying drawings, in which:—

Fig. 1 is a side elevation view of a magneto embodying the invention, certain parts being broken away to reveal interior construction;

Fig. 2 is a front elevational view thereof with the front casing removed to show certain magneto parts;

Fig. 3 is an elevational view taken from the right hand side of Fig. 2;

Fig. 4 is a diagrammatical view illustrative of the magnetic and electrical circuits of the magneto; and

Figs. 5, 6, 7 and 8 are fragmentary views, taken similarly to Fig. 1 and illustrating successive steps in the operation of the magneto.

Referring to these drawings:—The magneto include a suitable source of magnetic flux, herein shown as a series of bar magnets 10, to the poles of which are suitably and magnetically connected two laterally spaced and depending cores 11, preferably made up of laminations in the usual manner. On each core 11 is a suitable generating coil 12 and a choking coil 13, the coils 12 being suitably connected, as in series as indicated in Fig. 4, and the coils 13 being similarly connected, as there indicated. An armature 14, preferably made up of laminations in the usual manner, is mounted in any suitable manner for movement toward and away from the lower end of at least one of the cores, and usually away from the lower ends of both of the cores 11. These core ends constitute magnetic poles and the object of the armature movement, however effected, is to vary the reluctance of the magnetic circuit, whatever its particular nature. As shown, such circuit comprises the source 10, cores 11, armature 14, and the air gaps between the latter and its poles. The precise arrangement of the magnetic circuit and the means for effecting variations therein are not essential features of the present invention.

The terminals of the connected coils 12,

which together form the generating winding, are connected to the ignition system in any usual and desired manner. Usually one terminal of the winding is grounded, as indicated at 15, and the other terminal is connected, as by a wire 16, to a spark plug 8, or the wire 16 may, when the magneto is used in connection with multi-cylinder engines, lead to a distributor. The choking winding, afforded by the connected coils 13, is arranged in an electrical circuit which can be opened and closed by two cooperating breaker points 17 and 18, one of which, as 18, is connected metallically, as will appear, to the frame of the machine and is thus "grounded". One terminal of the choking winding is likewise grounded, as indicated at 19, and the other terminal is connected by a wire 20 to a breaker point 17. A condenser 21 is bridged across the breaker points in the usual manner, being connected by wires 22 and 23 to point 17 and ground 19, respectively.

The breaker point 17, as shown in Fig. 1, is stationarily, but adjustably, fixed in and insulated from the upper end of a tube 24, which in turn is suitably fixed in a metallic but non-magnetic part 25 of the magneto frame. The breaker point 18 is mounted in the upper end of a cylinder 26 which is 95 100 105 110 115 120 125 130 135 140 145 150 155 160 165 170 175 180 185 190 195 200 205 210 215 220 225 230 235 240 245 and the details of the construction and arrangement of parts are not important to, or essential parts of, the present invention.

The armature 14 may be mounted for movement toward and away from the end of one or both of the cores 11 in any suitable manner, as above set forth. As shown, the armature is slideable in a straight line on a guide pin 35 which is fixed to the frame member 25 and extends downwardly therefrom, passing freely through the central portion of armature 14. Centrally fixed to the latter and depending therefrom is a fork 36, the depending arms of which are bridged and interconnected by a pin 37. The latter is received in the forked outer extremity of an arm, 38, integral with which is a depending arm 39,—the two arms forming a bell crank lever which is pivotally mounted at the junction of the arms on a stud 40. The arm 39 constitutes a follower for a cam 41, fixed on a shaft 42, suitably driven at the desired speed ratio from the engine crankshaft. A spring 43, mounted in a recess 44 provided in bracket 33, acts on the lower end of an arm 39 and tends to hold it in engagement with cam 41.

The armature operating means is differentiated from that ordinarily employed in magnetos of this general type in that the armature is at all times operated by an inelastic transmission from the driving shaft. The usual drive spring, which is stressed during the revolution of such shaft and subsequently released to move the armature at a speed independent of engine speed, is entirely dispensed with for the present magneto is intended for use with engines wherein armature speeds, equal to or in excess of those obtainable by drive springs, can be obtained by the operating means herein disclosed.

The stud 40 is fixed to a collar 45 in eccentric relation therewith and projects outwardly therefrom in the fashion of a crank pin. Fixed to collar 45 in concentric relation therewith, and thus eccentrically with relation to stud 45, is a shaft 46 which is mounted to turn in a bearing 47 formed on bracket 33. Integral with bracket 33 and concentrically disposed with relation to shaft 46 is a sector 48, the curved edge 49 of which is notched, as shown in Fig. 3. Fixed to shaft 46 is an arm 50, the hub of which functions as a collar and cooperates with collar 45 and the end faces of bearing 47 to limit the end play of shaft 46 therein. Arm 50 is adapted to swing adjacent sector 48 and is provided with a cylindrical portion 51 which overlies the curved edge 49. Mounted in portion 51 is a spring pressed detent 52 which is constantly urged toward the edge 49 and is adapted to engage in any of the notches therein to hold shaft 46 in various positions of angular adjustment in

bearing 47. By turning arm 50, the stud 40 may be raised and lowered and also moved laterally with respect to the center of shaft 46 and consequently the pivotal axis of the armature actuating bell crank lever may be varied. The important effect of this variation of the location of the pivotal axis is to control the degree to which the armature 14 approaches the ends of cores 11 or the extent of the minimum air gap therebetween. The stud 40 may be so positioned that armature 14 can come into physical contact with cores 11 or it may be so positioned, as illustrated, to prevent such contact and so limit the degree of approach of the armature to cores 11 that a minimum air gap such as α , (Fig. 1), is left therebetween. Also the extent of this air gap α may be varied within limits, as desired.

The results described follow for two reasons. First, if the stroke of the armature 14 be regarded as constant, then the location of this stroke with respect to fixed parts of the magneto is varied by the vertical movements of adjustments of stud 40. Second, the vertical movements of stud 40, as a matter of fact, cause cam 41 to engage arm 39 along lines of contact which are at different distances from the center of stud 40, whereby the effective length of arm 39 may be varied to vary the extent of stroke of the armature.

Fixed on shaft 42 adjacent cam 41, is a cam 53, which has a function in controlling the operation of the breaker point mechanism. Cam 53 has substantially equal low and high dwell portions 54 and 55 respectively, of nearly 180 degrees extent, connected by short rise and fall portions 56 and 57 respectively. Engageable with cam 53 is a suitable cam follower 58, herein shown as a lever pivoted to bracket 33 at 59 and underlying cam 53, being yieldingly held in contact with the latter by a spring 59'. The free end of lever 58 is bent at right angles, as shown at 60 in Fig. 2, to lie vertically beneath the end of the breaker point stem 27. A link 61, one end of which is inturned and engaged in a hole in the end 60 of lever 58, extends upwardly and enters freely into the bottom of sleeve 62. The latter is fixed, preferably in an adjustable manner, as shown in Fig. 1, to the lower end of stem 27 and below the latter has a cylindrical bore 63 in which a head 64, fixed on link 61, is freely slideable. The arrangement is such that stem 27 and the attached sleeve 62 may move downwardly independently of link 61, whereby the breaker points 17 and 18 may be separated in the usual way by the engagement of abutment 28 on the armature with abutment 29 on stem 27. The arrangement is also such that lever 58 may be depressed by cam 53, thus drawing link 61 down-

wardly until head 64 engages and moves sleeve 62 and thus moves the breaker point 18. The various parts in the breaker point operating mechanism being adjustable, they 5 may be adjusted and timed so that either means can operate the breaker points. By preference, however, the latter are opened in the usual manner by the movement of the armature and are prevented from again 10 closing by the operation of cam 53 until the armature has reached the upper limit of its travel. The prevention of the closing of the breaker points is important in that the flux is permitted to build up rapidly in the 15 magnetic circuit, since the choking coils 13 are prevented from exercising their retarding influence which would occur if the breaker points were in contact. The breaker points are allowed to close after the armature 20 has dwelled in its upper position for a sufficient interval to permit the flux to build up in the magnetic circuit.

The armature driving means, as above disclosed, includes a cam and desirably this 25 cam is a quick throw cam of the general type illustrated. The particular contour of cam 41, and the manner in which it coacts with follower 39, is important because of the resulting effects obtained in the operation 30 of the armature and the breaker point mechanism. The greater portion of cam 41 is concentric with shaft 42 and the concentric portions are made up of a relatively large low dwell portion 65 and a relatively 35 small high dwell portion 66. The portions 65 and 66 are connected by rise and fall portions 67 and 68, respectively,—these portions being straight and arranged in outwardly converging relation. In the counterclockwise rotation of cam 41 (as viewed 40 in Fig. 1) the portion 67 will eventually move into parallel and contiguous relation with the follower 39. This occurs after cam 41 has moved through the angle α and the 45 relative positions of the parts which then obtain is illustrated in Fig. 5. Thereafter, continued movement of cam 41 moves the follower and the armature 14 but the movement of the latter, at least in its initial 50 stages, is relatively slow as the contiguous faces 39 and 67 begin to move out of parallelism. The relatively slow initial movement is followed by a progressively and rapidly increasing movement which 55 reaches its maximum as the parts move into the relative positions shown in Fig. 6. The condition there illustrated is that which obtains at the end of the movement of follower 39. During the movement of cam 41 through the relatively small angle b , the armature 14 is moved away from poles 11 and to the lower limit of its downward stroke. The action is therefore not only 60 very quick but the armature is started in motion relatively gradually and with as

little shock as possible. The relatively gradual initial action is especially important when the condition of physical contact exists between the armature and its cores. The powerful magnetic hold then existing 70 between these elements is broken in a highly effective manner and in one calculated to produce the least wear and tear on the parts at high speed. Having thus started the armature in motion, quick acceleration is 75 then desired to get the armature moving at high speed and when the armature has attained the requisite speed, the breaker points are separated and moreover, are separated at high speed to cause a quick break 80 and one which is least apt to have detrimental effects on the breaker points. Note that the breaker points do not separate during the initial movement of the armature. At this stage, the spring tension is 85 diminished although not entirely relaxed but separation of the points does not occur until the abutments 28 and 29 engage and these engage only after the armature has acquired considerable speed. The breaker 90 points being closed, the choke winding tends to prevent a rapid change of flux in the magnetic circuit and the breaker points may be likened to a valve for, as soon as they are opened, the flux is released and, 95 the armature having moved a considerable part of its stroke away from the poles and established a substantial air gap therebetween and acquired a high rate of speed, a sharp change of flux in the magnetic circuit ensues, resulting in the production of 100 a substantial spark.

The cam 41, as it moves through the angle c , has no effect in moving the armature and the latter dwells in its lower position. As 105 cam 41 continues to move, however, the armature is moved toward its poles again and in a reverse manner to that already described. That is, it moves rapidly at first and progressively decreases in speed as it 110 approaches the poles. After the cam 41 has moved through the angle d , the armature has then approached as closely to poles 11 as the adjustment of the stud 40 permits and dwells in this position during the travel of 115 cam 44 through angles e and a . It is to be noted, however, that the breaker points are prevented from closing during the upward flight of armature 14 because at the time when cam 41 moved the armature into the lowermost position the portion 56 of cam 53 came into action to lower the lever 58. Thereafter, the armature moves toward poles 11, the head 64 restrains the upward movement of breaker point 18, which would otherwise be permitted by the armature. Consequently, the breaker points are allowed to engage only after cam 53 permits and this is permitted only after the armature has attained the uppermost position and has re- 120 125 130

mained in that position long enough to build up the desired amount of flux in the magnetic circuit, at which time the lever 58 quickly releases the breaker points and allows them quickly to engage.

The general operation of the magneto having been explained, it remains to consider the special features relating to the means whereby the minimum air gap between the armature and its poles may be varied. As above set forth, the arrangement is such that the armature may contact with its poles, thus affording a minimum reluctance for the magnetic circuit by the entire elimination of air gaps, the reluctance of which, as is well known, is exceedingly high. The provision for contact between the armature and poles is desirable for starting because it is assumed that relatively low armature speeds will then be available.

After starting, the lever 50 is turned to vary the position of stud 40 so that contact of the armature and poles is eliminated. By so doing, the noise and the wear and tear on parts incident to such contact is eliminated and the electrical output is governed so that if sufficient for low speeds it will not be excessive on high speeds. The elimination of contact is a practical necessity in a magneto of this type intended for high speed operation for by preventing contact of armature and poles, substantially all the noise of operation is eliminated and the magneto operates very quietly and is sufficiently noiseless so that its use on an automobile is entirely unobjectionable from this point of view. There are no parts which are subjected to heavy blows at high speed or exceptionally rapid wear so that the life of the magneto can be at least as great as any of the magnetos ordinarily used on automobiles. While the elimination of noise entails the existence of air gaps between the armature and poles, higher armature speeds are available when used in the described manner in connection with automobile engines, or other multi-cylinder types than in single cylinder stationary engines, with which this type of magneto has been associated in the past. Armature speeds equal to, or greater, than those obtained by spring drive may be obtained and a greater armature speed can be chosen to compensate for the necessary air gaps. Magnets with higher flux values may be chosen for the magnetic source to compensate for the presence of the air gaps. In fact, the magnetic flux and armature speeds may very easily be made such that it is necessary during normal high speed operation to create the air gap between the armature and its poles in order to prevent the generation of an excessive electro-motive force which would puncture the windings and otherwise work injury in

the electrical circuits. The arrangement, however, is such that the minimum air gap may be varied, as desired, to secure the desired results. On some installations the minimum air gap may be as small as it can be made without actual contact occurring. On others, minimum air gaps of greater degree may be required and the adjustments described allow one to control and govern the electrical output of the magneto as desired.

In connection with the means for varying the minimum air gap between the armature and its poles and in addition to the important resultant advantage of controlling the electrical output of the magneto as required, there is another important feature which should be noted. The arrangement is such that the operator cannot get a back kick by cranking the engine even if the spark should be advanced. This result follows from the fact that an advance in the timing of the spark simultaneously effects the creation of an air gap and the creation of an air gap so increases the reluctance of the magnetic circuit that it is impossible to get a sufficient spark at cranking speeds under these conditions.

While the elimination of contact of the armature with its poles is important and essential to the practical and commercially satisfactory operation of a magneto, of the general class described, at high speeds, there is another important factor which contributes substantially to the successful operation of the magneto at high speed. This factor is the means for preventing the breaker points from closing on the upstroke of the armature. While the flux can be built up in the magnetic circuit with the choking winding short circuited, the action is necessarily slow as the function of the choking winding is to retard changes of flux in the magnetic circuit. In low speed magnetos, sufficient time may be afforded in which to build up the flux against the short circuited choking winding and thus decrease the noise due to the magnetic attraction on the armature but in the present case the available time interval is very short and it is essential to eliminate every retarding influence. Consequently, the breaker points are purposely held open to expedite the building up of the flux in the magnetic circuit and the elimination of the noise has been otherwise provided for.

It is also to be noted that the timing of the spark is determined by the time of opening of the breaker points or by the time of engagement of abutments 28 and 29. This time may be varied by adjustment of the abutment 29 and obviously it may equally well be varied by moving the abutment 28 instead. The adjustment of stud 40 by lever 50 does, in fact, also vary the timing

and does so by adjusting the abutment 28 toward or away from abutment 29. The time of flight of the armatures may occur substantially at the same time in each revolution of cam 41 but the time of spark may occur earlier or later according to the distance existing between abutments 28 and 29, when the armature is in its uppermost position. When the armature is in contact with its poles, the spark occurs later in the armature flight and thus later in the revolution of shaft 42 than it does when the armature is positioned as shown in Fig. 1. Consequently, when the lever 50 is manipulated to cause the armature to contact with its poles, for starting purposes, the spark is automatically retarded, as it should be, and independently of the operator, as is desirable. As lever 50 is moved to prevent contact of armature and poles or to running position, the spark is at the same time automatically advanced.

I believe myself to be the first to provide a magneto of the general class described with operating mechanism whereby the degree of approach of the armature to its poles may be varied as desired and where the armature can be made to contact with its poles or not, according to the condition desired. I also believe myself to be the first to provide, in connection with breaker point mechanism controlled from the armature movement, a supplementary controlling means independent of the armature for the general purposes set forth. Accordingly, I desire to claim my invention in the broadest possible legal manner.

What I claim is:—

1. In a magneto, of the type wherein a reciprocating armature is movable toward and away from a stationary magnetic pole to vary the reluctance of a magnetic circuit, means for varying the reciprocating movement of said armature to vary the degree to which the armature approaches to said pole.

2. In a magneto, of the type wherein an armature is movable toward and away from a magnetic pole, controlling means operable on the armature to enable it to contact with said pole or be held from contact therewith as desired.

3. In a magneto, of the type wherein an armature is movable toward and away from a magnetic pole, means for controlling the movement of the armature to enable the minimum air gap between the armature and said pole to be varied.

4. In a magneto, of the type wherein an armature is reciprocable in a straight line toward and away from a stationary magnetic pole, means for varying the minimum air gap between the armature and said pole, and reducing it to zero when desired.

5. In a magneto, of the type wherein an

armature is movable into and out of contact with a magnetic pole, means acting on the armature to prevent it from being moved into contact with said pole when desired.

6. In a magneto, of the type wherein an armature is movable into and out of contact with a magnetic pole, means acting on the armature for preventing such contact when desired without interfering with the freedom of movement of the armature. 75

7. In a magneto, of the type wherein an armature is movable toward and away from stationary magnetic poles, an operating shaft and connections therefrom to said armature for moving the latter from the former by an inelastic transmission of force therefrom at all times, and means for controlling the movement of the armature to thereby vary the minimum air gap between the armature and poles. 85

8. In a magneto, of the type wherein an armature is movable into and out of contact with stationary magnetic poles, an operating shaft and connections therefrom to said armature for moving the latter from the former by an inelastic transmission of force therefrom at all times, and adjustable means acting on the armature without interfering with its freedom of movement for preventing the armature from contacting with said poles. 90

9. In a magneto, of the type wherein an armature is movable toward and away from a magnetic pole, means for reciprocating the armature, and means for varying the location of the reciprocating movement with respect to said pole. 95

10. In a magneto, of the type wherein an armature is movable toward and away from a magnetic pole, means for reciprocating the armature, and means for varying the stroke of said movement to vary the degree to which it approaches said pole at the end of one stroke of its movement. 105

11. In a magneto, of the type wherein an armature is movable toward and away from a magnetic pole, means for varying the degree to which the armature approaches said pole, and means operable from the first named means for varying the timing of the spark. 110

12. In a magneto, of the type wherein an armature is movable toward and away from a magnetic pole, means for varying the minimum air gap between the armature and said pole, and means for advancing or retarding the spark generated accordingly as the minimum air gap is increased or diminished, respectively. 115

13. In a magneto, of the type wherein an armature is movable toward and away from a magnetic pole, means for controlling the degree to which the armature approaches said pole and capable of allowing the armature to contact therewith, and means con- 120

- trolled by said first named means for timing the spark generated by the magneto.
14. In a magneto, of the type wherein an armature is movable toward and away from a magnetic pole to vary the flux in the magnetic circuit, a frame stationary with respect to said pole, cooperating and relatively movable breaker points, an abutment on the armature, an abutment carried by the movable breaker point adapted to be engaged by the first named abutment to separate said points, means yieldingly holding said points in contact and the second named abutment stationary with respect to said frame, means for operating the armature, and means for adjusting the position of the latter with respect to said pole to vary the spacing between said breaker points and the timing of the generated sparks.
15. In a magneto, of the type wherein an armature is movable toward and away from a magnetic pole to vary the flux in the magnetic circuit, a frame stationary with respect to said pole, cooperating and relatively movable breaker points, an abutment carried by the movable breaker point, a second abutment, means for moving the latter from an initial position to engage the first named abutment and separate the breaker points, and means for varying the initial position of the second abutment.
16. In a magneto, of the type wherein an armature is movable toward and away from a magnetic pole to vary the flux in the magnetic circuit, a frame stationary with respect to said pole, cooperating and relatively movable breaker points, an abutment carried by the movable breaker point, a second abutment, means for moving the latter from an initial position to engage the first named abutment and separate the breaker points, and means operable during the operation of the armature and said mechanism to vary the initial position of the second abutment.
17. In a magneto, of the type wherein an armature moves away from an initial position in close proximity to magnetic poles to a second position remote from said poles to generate a spark and immediately returns to said initial position wherein it dwells until subsequently moved away to generate another spark, a choking winding associated with said poles and arranged in an electrical circuit which can be opened and closed, cooperating and relatively movable breaker points for controlling the opening and closing of said circuit, means adapted to hold said breaker points in contact when the armature occupies its initial and dwell position, means operable by movement of the armature away from its poles for separating said points after it has moved away from the initial position and before it reaches the second position, and means for preventing the breaker points from closing during the return movement of the armature and until it has come to rest in said dwell position.
18. In a magneto, of the type wherein an armature moves away from an initial position in close proximity to magnetic poles to a second position remote from said poles to generate a spark and immediately returns to said initial position wherein it dwells until subsequently moved away to generate another spark, a choking winding associated with said poles and arranged in an electrical circuit which can be opened and closed, cooperating and relatively movable breaker points for controlling the opening and closing of said circuit, means adapted to hold said breaker points in contact when the armature occupies its initial and dwell position, means operable by movement of the armature away from its poles for separating said points after it has moved away from the initial position and before it reaches the second position, and means to hold the breaker points open during the return stroke of the armature and for releasing them for closure under the first named means after the armature has come to rest and is dwelling in said initial position.
19. In a magneto, of the type wherein an armature is moved toward and away from a magnetic pole, breaker point mechanism including a movable breaker point, a drive shaft from which said armature is actuated, means on the armature for moving said point in one direction and means operable from said shaft for controlling the movement of said point in the other direction.
20. In a magneto, of the type wherein an armature is moved toward and away from a magnetic pole, breaker point mechanism including a movable breaker point, a drive shaft from which said armature is actuated, means controlled by movement of said armature for separating said points, and means controlled from said shaft for controlling the closing of said points.
21. In a magneto, of the type wherein an armature is moved toward and away from a magnetic pole, breaker point mechanism including a movable breaker point, yieldable means tending to hold said points in contact, an abutment carried by said movable point, an abutment on the armature engageable with the first named abutment during its movement away from the pole to separate said points, and means for preventing said points from closing under the action of said yieldable means as the armature moves back toward said pole.
22. In a magneto, of the type wherein an armature is moved toward and away from a magnetic pole, breaker point mechanism including a movable breaker point, yieldable means tending to hold said points in

contact, an abutment carried by said movable point, an abutment on the armature engageable with the first named abutment during its movement away from the pole

5 to separate said points, a second abutment carried by said movable point and means independent of the movement of said armature for engaging the last named abutment and holding said breaker points open after 10 the first abutment on the movable point has been released by the cooperating abutment on said armature.

23. In a magneto, of the type wherein an armature moves toward and away from a 15 magnetic pole to vary the reluctance of a magnetic circuit by increasing or diminishing an air gap therein, means for varying

the degree to which the armature approaches said pole to thereby vary the electrical output of the magneto and compensate for variations in armature speed. 20

24. In a magneto, of the type wherein an armature is movable toward and away from a magnetic pole to vary the reluctance of a magnetic circuit, means for varying the 25 timing of the sparks generated by the magneto, and means controlled by the variation in timing to increase or diminish the electrical output of the magneto at any given armature speed accordingly as the spark is 30 retarded or advanced.

In testimony whereof I have affixed my signature.

PHELPS BROWN.
